United States Patent Office.

JOHN SCHUMACHER AND HENRY UPJOHN, OF ANN ARBOR, MICHIGAN.

Letters Patent No. 80,511, dated July 28, 1868.

IMPROVED MACHINE FOR PRESSING AND GROOVING SEAMS IN TIN-WARE.

The Schedule referred to in these Letters Patent and making part of the same.

TO ALL WHOM IT MAY CONCERN:

Be it known that we, JOHN SCHUMACHER and HENRY UPJOHN, of Ann Arbor, in the county of Washtenaw, and in the State of Michigan, have invented certain new and useful Improvements in Machines for Grooving and Pressing Seams in Tin-Ware; and do hereby declare that the following is a full, clear, and exact description thereof, reference being had to the accompanying drawings, and to the letters of reference marked thereon.

In the annexed drawings, making part of this specification, A represents the base of this machine, which may consist simply of a block of sufficient size and weight to keep the machine steady in its place. Upon this base is erected a standard, B, which is made of metal, and divided or made double at its upper end. Projecting from this standard are two arms, C and D, said arms being made of metal, and placed parallel to each other a suitable distance apart. Between these two arms is placed a rack-bar, E, with its teeth projecting downward. This rack-bar is moved by means of a pinion, G, seen in dotted line, and secured upon a shaft which runs crosswise through the standard B. The shaft is provided with a crank-handle, by means of which it is revolved, and the pinion rests between the two parts of the standard.

That end of the bar E which plays between the arms C and D, is secured between two metal-jaws, I I'. These jaws embrace the arm D, and have a bolt, e, passed through, above said arm, to secure them to it, and also to regulate the position of the bar E. The jaws are to be perforated with several holes, so that the bolt can be shifted, in order to raise or lower the bar E at pleasure.

Between the jaws I, and at the end of bar E, is secured a corrugated roller, J. To the upper side of bar E, and above the roller J, is secured a strong spring, and to this spring is connected a friction-roller, α . The roller J plays, when the machine is not in use, against the lower arm C, and the roller α plays all the while against the arm D.

H represents a slotted gauge-plate, which is secured to the side of the arm C, and which is capable of adjustment longitudinally upon said arm.

In using this machine, the tin, after being bent in the usual manner for forming a joint, is placed with its joint upon the arm C, beneath the groove or corrugation in the roller J, the inner edge of the pieces of tin resting against the gauge H. The rack-bar E is then operated by the pinion G, so that the roller J is passed over the seam or joint. The roller presses the groove in the joint as it passes over it, being pressed down firmly upon it by the spring upon the upper side of the rack-bar, and to which the friction-roller α is attached. The portion of roller J, marked α , presses the edge of the seam down.

The gauge H serves to regulate the distance which the tin passes over the arm C, and also acts as a rest for its inner edge while it is being operated upon.

We are fully aware that the machine composed of the arms C D, rack-bar E, having a roller on its end, and operated substantially as herein set forth, is not new. Our invention only consists in the adjustability of the rack-bar, the construction of the roller, and the addition of the gauge.

Having thus fully described our invention, what we claim as new, and desire to secure by Letters Patent, is—

The gauge H, used in combination with the arm C, as and for the purpose set forth.

In testimony that we claim the foregoing, we have hereunto set our hands, this 25th day of March, 1868.

JOHN SCHUMACHER,
HENRY UPJOHN.
